RICHARD LESTER WILCOX AND THOMAS NOLAN, OF WATERBURY, CONNECTICUT,
ASSIGNORS TO THE WATERBURY FARREL FOUNDRY AND MACHINE COMPANY,
OF WATERBURY, CONNECTICUT, A CORPORATION OF CONNECTICUT.

DIE FOR TRIMMING BLANKS.

1,294,991.

Specification of Letters Patent. Patented Feb. 18, 1919.

Application filed February 26, 1918. Serial No. 219,173.

To all whom it may concern:

Be it known that we, RICHARD LESTER WILCOX and THOMAS NOLAN, both citizens of the United States, and residents of Waterbury, county of New Haven, State of Connecticut, have invented certain new and useful Improvements in Dies for Trimming Blanks, of which the following is a specification.

10 Our invention relates to improvements in dies for giving a trimmed cross section to a blank as is done, for instance, in forming the square, hexagonal or octagonal shapes of bolt heads, nuts and the like, or a many-sided shape of any kind, such for instance, as a circular section with flat sides, as is formed on shackle bolts and the like. It will be understood that by "polygonal" or "polygon," we mean any such shape. A

15 blank may also be cut so as to have a circular section, and when we refer hereinafter to a "trimmed" section, it will be understood that we mean a section of any shape which has been cut or trimmed by the dies, either entirely around it or on any particular portion.

One of the objects of our invention, among others, is to produce a die which is provided with removable cutting edges so that they may be readily ground and sharpened, while at the same time having substantially the same strength as that of a solid die.

Another object of our invention is to produce a die which will not only give a trimmed section to the blank but will also planish in the same die the surfaces thus formed.

In the accompanying drawings, Figure 1 represents in perspective an illustrative form of die embodying our invention;

Fig. 2 is a plan view of the die;

Fig. 3 is a side elevation of one of the cutters, looking in the direction of the arrow 4 of Fig. 2;

Fig. 4 is an elevation of two of the cutters looking in the direction of the arrow 3 of Fig. 2;

Fig. 5 shows a bolt finished from the die shown in Fig. 1; and

Fig. 6 shows a variation in the formation of the cutters.

The corresponding parts are referred to both in the drawings and in the specification by similar reference characters.

55

In the drawings 10 represents a body member which, in the form illustrated, is provided with an opening 11, which in this instance, is hexagonal. The specific form of die used for purposes of illustration is intended to form hexagon heads on nuts and the like, and there are provided therefor cutting members so arranged as to form a hexagonal opening in the die with the cutting edges forming a hexagon of the desired size.

60

Preferably each of the cutting members 12 is given the same section which in the form illustrated is a trapezoid in which the two sides which are not parallel, form equal but opposite angles with the other sides of the figure. The top of each of these cutters is cut away at an angle so that the cutting edges 13 will have an angular relation to the direction of movement of a blank in the die. In the form illustrated in Figs. 1 to 4 inclusive, the cutters are arranged so that each pair of these cutting edges form opposing angles of shear.

70

Each of the cutters is preferably provided with a screw 14 by which it is held in the body member 10.

80

It will be understood that the die is used by placing it against any suitable bench or other support, so that the longitudinal cutting pressure, which is the principal one, will be taken up directly by the support. Whatever lateral pressure there is will be taken up by the solid ring of the member 10 either by direct pressure against its walls or against the ends of the screws 14.

90

A slight taper is given to the faces of the cutters 12 carrying the cutting edges 13. This is to provide proper clearance for the cutting edges. Consequently, when the top angular faces of the cutters are ground to sharpen the cutters, the cutting edges will be somewhat farther from the axis of the die than originally, and this will produce a blank slightly larger than the blank cut before the cutters were ground. In order to restore the die to its original size, the sides of the cutters marked 4 in Fig. 2 are also ground and then by adjusting the screws 14, the cutting edges 13 may be moved to their

95

100

required positions. If the planishing surfaces 15 are formed directly on the cutter, they must also be ground to make the correct size of opening. But if, as explained herein-after, the planishing surfaces are on separate pieces, no such grinding of those surfaces is required.

In Fig. 6 a pair of cutters is shown in which the angles of two adjacent cutters are 10 parallel, the cutters being otherwise the same as those illustrated in Fig. 2. That is to say in this form of cutter, the cutting edges extend generally in the same direction from top to bottom of the die instead of in opposite directions as in the form illustrated in Fig. 4, so that in Fig. 6 the chips from adjacent cutters will be thrown in the same direction.

When a blank, such as a bolt head, is 20 forced into our novel die illustrated in Fig. 2, the pressures on the respective cutting faces, in a direction around the axis of the die as a center, will balance each other, so that there will be no tendency for the blank 25 to rotate as it is being cut. The direction of pressure of cutting is indicated by the lines *a—a* and *b—b* of Fig. 5. With the arrangement shown in Fig. 6, since all of the lateral strain of cutting is in the same direction around the blank, there will be a tendency for the blank to rotate. Consequently the form shown in Fig. 2 is the preferable one.

In order to iron, smooth and polish the 35 surface of the faces formed by the cutting edges 13, a slight projection 15 is preferably provided on each of the cutters. We have illustrated this projection as a flat face but it will be understood that any suitable form 40 will suffice, so long as it is sufficient to planish the blank as it is forced between these projections. It will be understood, moreover, that this projection is very slight and not as great as shown, for instance 45 in Fig. 3, where it is exaggerated for purposes of illustration. It will also be understood that the cutters and planishing members may be made of separate pieces, placed the one on the other, as if the cutter 50 members 12 were cut in two along a line parallel to the base and above the planishing surface.

While we have shown a form of cutter 55 which has a section adapted to hold the cutters in place in the body member after they have been once assembled, it will be understood that this is not essential, and any other form of section may be used. Preferably, however, the cutters should be 60 arranged so that only the lateral cutting pressure is taken up directly by the body member 10, either directly or through the screws 14, while the longitudinal cutting pressures are taken up by the bench or support on which the die is placed.

If necessary, additional screws 14 may be provided to take up the lateral pressure on the cutters, or any other suitable form of adjustment may be used.

We claim:

1. A die comprising a body member and a plurality of cutting members held therein, each of the members having a cutting edge and the members being constructed and arranged and held in the body member so as 70 to form an opening therethrough, with the cutting edges forming the periphery of the opening, each of the members having a slight projection across the face adjacent the opening and parallel with the plane passing 75 through the cutting edge on that face, parallel to the axis of the opening.

2. A die comprising a body member and a plurality of cutting members held therein, each of the members having a cutting edge 85 and the members being constructed and arranged and held in the body member so as to form an opening therethrough, with the cutting edges forming the periphery of the opening, and a planishing member having 90 its operative surfaces in the rear of and parallel to the plane passing through the cutting edges parallel to the axis of the opening.

3. A die comprising a body member having a polygonal opening therethrough, a plurality of cutting members in the opening equal in number to the number of sides of the opening, each of the cutting members having a cutting edge, the members 100 being arranged in the opening so that the cutting edges form a polygon similar to the polygon of the opening with the corresponding sides of the two polygons parallel.

4. A die comprising a body member having a polygonal opening therethrough, a plurality of cutting members in the opening equal in number to the number of sides of the opening, each of the cutting members being a polyhedron with two parallel faces, 110 one of which is narrower than the other, with a cutting edge formed on the narrower face, each member being held in the polygonal opening of the body with the wider of the two parallel sides parallel with one of 115 the walls of the opening.

5. A die comprising a body member having a polygonal opening therethrough, a plurality of cutting members in the opening equal in number to the number of sides of 120 the opening, each of the cutting members being a polyhedron with two parallel faces, one of which is narrower than the other, with a cutting edge formed diagonally across the narrower face, each member being 125 held in the polygonal opening of the body with the wider of the two parallel sides parallel with one of the walls of the opening.

6. A die comprising a body member and a plurality of cutting members therein, each 130

- having a flat face with a cutting edge extending diagonally across it, the members being positioned relatively so that the flat faces thereof form a polygonal opening 5 through the die with the cutting edge on one of the cutting members forming an angle with the cutting edge on an adjacent cutting member.
7. A polyhedral cutting member for a die, 10 having a flat face, a cutting edge on the face and a slight projection extending across the face.
8. A die comprising a plurality of similar cutting members with their bases in the same plane and a cutting edge on each member 15 at its top, the members being positioned in contact with each other so that the faces having the cutting edges form a polygonal opening, and a member surrounding the cutting members, to prevent relative lateral movement of the members.
9. A die comprising a plurality of cutting members with their bases in the same plane and a cutting edge on each member at its 20 top, the members being positioned around an axis with their sides contacting and with the faces having the cutting edges forming a polygonal opening around the axis, the 25
- contacting sides being constructed to prevent the members moving toward the axis 30 and a member around the cutting members to prevent movement away from the center.
10. A die comprising a plurality of cutting members, each having a cutting edge at its top, the members being positioned with 35 their sides contacting to form an opening through the die with the cutting edges forming the periphery of one end of the opening, the contacting sides being constructed to prevent the members moving toward the 40 axis and a member around the cutting members to prevent movement away from the opening.
11. A die comprising a plurality of cutting members, each having a cutting edge at 45 its top, the members being positioned with their sides contacting to form an opening through the die with the cutting edges forming the periphery of one end of the opening, the contacting sides being constructed to prevent the members moving toward the 50 axis and adjustable means to prevent the members moving away from the opening.
